MECHANISM FOR FORMING ENDS OF METALLIC CYLINDERS

Raymond Kargard, Peter Kargard, and Allen C. Kargard, Marinette, Wis., and Hilmar A. Andresen and Raymond H. Andresen, Barrington, Ill., assignors to The Kargard Company, Inc., Marinette, Wis., a corporation of Wisconsin

Filed Aug. 20, 1957, Ser. No. 679,222

4 Claims. (Cl. 113—52)

The present invention relates to improvements in metal forming apparatus and more specifically to a mechanism for closing the end of a length of hollow cylindrical metal tube.

In metal forming and spinning operations, the ductility of the metal is usually taken advantage of by stretching the metal into the forms required. In most instances, it is impractical to roll from a large diameter to a small diameter and this requires swaging in a manner that increases the thickness of the metal at the small diameter. The present invention contemplates providing a mechanism capable of producing a closure at the end of a tube and particularly capable of producing a closure on the end of a tube, such as a thin wall welded tube.

Articles of this nature have been formed heretofore by forming a curved cup which is welded to the end of a cylindrical tube to complete the article. This method has been objectionable in that the product contains an unsightly weld, and that the manufacture requires an additional part. The present invention, therefore, contemplates improving the product and reducing the time and cost of manufacture by spinning or rolling the end of the cylindrical tube into the required shape with the article being formed of a single unitary section of material.

In one form of mechanism embodying the principles of the invention, a plurality of shaped form rollers having a curved grooved surface are radially disposed in circumferentially spaced open arrangement to rotate freely on canted axes which are set at an angle to the axis of a cylindrical tubular workpiece that is to be fed to the rollers to have the end formed and closed. Between the rollers is a support spider having arms carrying bronze faced concave support surfaces which hold the area of metal of the cylinder between the rollers in non-galling engagement. The cylindrical tubular workpiece is moved against the rollers and a circular form mandrel moved axially toward the rollers within the workpiece with the form mandrel having a rounded face to coact with the rollers. The form mandrel is stopped spaced from the rollers and the tube forced therebetween by a feed plate while the rollers and support spider are revolved about the axis of the cylindrical workpiece.

It is an object of the invention to provide a mechanism of the above nature which provides improved apparatus for forming and closing the end of a hollow elongated cylindrical tubular workpiece.

Another object of the invention is to provide an improved mechanism which will form a hollow tubular section of material with a closed end formed of a single unitary material, and shaped by decreasing the thickness of the tube in a progressive manner to form a curved closed end.

Another object of the invention is to provide an improved mechanism closing the end of a cylindrically shaped tube employing spaced formed rollers with means for preventing the metal from bulging between the rollers and for engaging the metal without galling the surface.

2

Another object of the invention is to provide an improved mechanism for closing the end of a tubular cylinder wherein opposed forming surfaces are employed which are shaped to be spaced from each other in an increasing thickness following the curvature of the material of the cylinder in an inward direction.

Other objects and advantages will become more apparent with the teaching of the principles of the invention in the disclosure of the preferred embodiments in the specification, claims and drawings, in which:

Figure 1 is an elevational view of a machine embodying the principles of the invention;

Figure 2 is a vertical sectional view taken through the machine embodying the principles of the invention and showing a tubular workpiece in place for operation of the machine, and taken along line II—II of Figure 4;

Figure 3 is a vertical sectional view similar to Figure 2 and showing the end of the tubular workpiece being formed;

Figure 4 is a horizontal sectional view taken through the machine, and illustrating the relative arrangement of the forming rollers and support shoes; and,

Figure 5 is a vertical sectional view taken along line V—V of Figure 4, with parts being removed for clarity.

The apparatus and method embodying the features of the invention are illustrated in connection with Figures 1 through 5, as used for forming and closing the end of a length of a hollow tubular cylinder 6, as shown in Figures 2 and 3. The tubular cylinder 6 may be constructed of a material such as brass, steel, or aluminum and may be a section of seamless tubing, such as is available commercially. While the invention is well adapted to handling tubing of various sizes and thicknesses, by way of example, a tube on the order of six inches in diameter may have the end closed inwardly to form an article such as a fire extinguisher tank. In this case a welded steel tube provides suitable material. It will be understood, however, various articles may be formed and the apparatus disclosed as embodying the principles of the invention is shown and described by way of illustration, and the features and elements of the invention may be used in other environments taking advantage of their inherent capabilities.

To form the tube by closing the end, the end 8 of the tube 6, Figure 2, is curved inwardly to complete the inwardly formed closed rounded end 10 which is shown in Figure 3.

The forming mechanism includes a plurality of shaped forming rollers 12, 14, 16 and 18 which are disposed radially of a center axis 20 of the tubular cylindrical workpiece 6. The rollers are circumferentially arranged and spaced in an open fashion so as to face upwardly to be engaged by the lower edge 8 of the tube in the manner shown in Figure 2 as it is advanced axially, which is in a downward direction as illustrated in Figures 2 and 3.

The rollers 12, 14, 16 and 18 are supported for free rotation about canted axes on bearing posts 22, 24, 26 and 28. The bearing posts are mounted on a base 30 and extend upwardly and outwardly to rotatably support the rollers 10. The bearing posts may carry bearing bushings 32, as illustrated for the roller 12 in Figure 3. The top of the post carries an enlarged head 34 to hold the roller on the post. The base 30 has a flat outwardly facing shoulder 36 to restrain the roller axially in a direction opposite the post head 34.

Between the rollers are upwardly inwardly facing curved support shoes 38, 40, 42 and 44. Each of these shoes has a soft facing which is preferably of bronze with the facings being illustrated at 46, 48, 50 and 52, in Figures 4 and 5. The bronze shoe facings have inwardly curved surfaces which are curved in two planes so as to relatively accurately fit against the curved end 10 of the tubular

cylinder at it is being formed. The shoes provide support for the formed end to prevent bulging as the metal is being shaped by the rollers. The bronze facing in the shoes permits sliding engagement between the support shoes and the formed tube end in a non-galling manner.

The shoes are supported in their circumferentially arranged spaced location between the rollers on legs, such as shown at 52 and 54 for the shoes 38 and 42 in Figure 5. The legs are part of a main support spider 56 which is supported coaxially with the center of the tubular workpiece 6 to properly locate and space the shoes. The spider is illustrated as having a centrally located hole 58 which permits it to be slid over a cylindrical boss or stop 60 projecting upwardly from the base 30. The centrally located stop 60, therefore, locates the spider and has an upwardly facing stop surface 62, which provides a limit for the downward axial movement of a form mandril 64.

The form mandril includes an enlarged end 66 carried at the end of a support rod 68. The form mandril has a leading downwardly facing rounded end which has a flat center portion 70, and which has an annular rounded edge 72. The rounded edge surface 72 cooperatively faces the inner facings 46, 48, 50 and 52 of the shoes, and also the surfaces of the rollers 12, 14, 16 and 18 to define a space therebetween for rolling and spinning the end of the tubular cylinder 6.

For providing the end closing space for the tube, each of the rollers have a concave annular grooved surface 74, such as illustrated for the roller 12 in Figure 1. This surface in profile has the same curvature as the facings for the shoes. The outer curved surface 72 of the form mandril is shaped to provide a forming space for the end 10 of the cylinder workpiece 6 therebetween, and the width of the gap between the rollers or shoe facings and the form mandril increases moving downwardly and inwardly around the curvature of the end 10 of the cylinder 10. That is, with reference to Figure 1, the thickness of the metal of the cylinder is shown at A, while at B the thickness is slightly greater and the thickness increases at C, and becomes increasingly thick at D. Thus, as the end 10 of the cylinder is being formed inwardly to close the cylinder end, the excess metal created by reducing the diameter of the tube is accommodated in increased thickness. This is caused by forcing the metal between the rollers and form mandril by forcing the cylinder 6 in a downward axial direction while preventing bulging between the rollers by the shoes.

The axial movement of the cylinder workpiece 6 is caused by a feed plate 76, shown as having a flat lower surface 78. A radial annular face 77 projects from below the surface 78 to center the tubular workpiece 6. The feed plate is illustrated by way of example as being circular in shape and mounted coaxially with the rod 68 carrying the form mandril 66. The plate 76 is supported on a pair of push rods 79 and 81 which connect to pistons 83 and 85. The cylinders are fixed in position being supported at 80 and are provided with connections for receiving a supply of operating fluid under pressure.

The tubular workpiece 6 is first set in place with the end 8 engaging the rollers 12, 14, 16 and 18, as shown in Figure 2. The form mandril 66 is then moved axially along its axis 20 toward the openly arranged upwardly facing rollers. The tubular workpiece 6 may be first slid over the form mandril, or the form mandril inserted from the end after it is positioned. For axial movement of the form mandril, the supporting rod 68 may be connected to a rod 76, Figure 1, connected to a piston housed within a fluid operated cylinder 84, which is anchored at 80. Suitable fluid lines lead to the cylinder 78 in a manner to cause reciprocation thereof, and by control valves the piston within the cylinder 78 is controlled, thus moving the piston rod 76 to position the form mandril. When the form mandril is moved downwardly, its lower flat surface 70 engages the upper end 62 of the stop 60 to prop-

erly space it from the rollers and from the support shoes.

The cylinder 6 is next axially thrust toward the rollers by axial movement of the feed plate 76 while simultaneously revolving the base 30 to carry the rollers around the tubular workpiece 6. The cylinder 84 for operating the form mandril and the cylinders 83 and 85 for the feed plate may be controlled manually or by automatic controls through mechanism which may be adopted by those skilled in the art following the teachings of the present disclosure.

For revolving the base 30 to carry the rollers around the tubular workpiece 6, the base may be supported on a lower shaft 86 for rotation about the vertical axis 20 of the workpiece. The base may carry a ring gear 88 which is driven by a mating pinion gear 90 carried on a drive shaft 92 of a motor 94. The motor may be electrically operated at the proper time and may be operated at a desirable speed for forming the end of the tubular workpiece 6. The rollers 12 which are mounted for free rotation on their posts, will form and close the end of the workpiece 6 as it is thrust axially in the space between the rollers and the form mandril with the support spider being rotated on the base with the rollers and preventing the metal from bulging out between the rollers.

It will be understood that the operating mechanisms for the form mandril 66, feed plate 76, and base 30, are shown by way of illustration, and various other types of drive devices may be readily adapted to operate the elements as described.

For each successive cylinder which is formed by having its end closed, the cylinder is positioned in its axial position against the rollers, and the form mandril 66 advanced against the stop 60. The feed plate 76 will then force the cylindrical workpiece 6 axially against the rollers 12, 14, 16 and 18. The rollers and the support plates 38, 40, 42 and 44 are rotated about the stationary workpiece 6 and the form mandril 66 to gradually form and close the end of the cylindrical workpiece 6.

Thus, it will be seen that we have provided an improved mechanism for forming the ends of metallic cylinders which meets the objectives and advantages hereinbefore set forth. The mechanism is well adapted for commercial operation and the methods are susceptible of use for numerous applications and purposes.

The method and apparatus of the invention form a completed closed end for a cylinder, and operate to close the end of cylinders in varying desired amounts. The completed cylinder presents a finished smooth article which is not marred by welds, and is quickly and inexpensively manufactured with the utilization of a single part, and with the end being made of the cylinder material.

We have, in the drawings and specification, presented a detailed disclosure of the preferred embodiments of our invention and it is to be understood that we do not intend to limit the invention to the specific form disclosed, but intend to cover all modifications, changes and alternative constructions and methods falling within the scope of the principles taught by our invention.

We claim as our invention:

1. A mechanism for forming and closing the end of a hollow tubular elongated cylinder which comprises a plurality of radially disposed circumferentially spaced rollers having annular concave forming surfaces and mounted for rotation about axes canted with respect to a feeding axis for a hollow cylindrical workpiece to be formed, individual support members between each of the rollers, curved arcuate bronze cylinder engaging surfaces on the support members for sliding engagement in a non-galling manner with the closing end of the cylinder, a spider having an axial center with radially extending arms carrying the support members with the bronze facings projecting between the rollers, a form mandril having an axially facing rounded annular surface curved to cooperate with the

surfaces of the rollers and supporting members to form the closed end of the workpieces therebetween, means for moving the form mandrel toward the rollers to an operating position with a work forming space between the mandrel and rollers, a stop means located between the rollers for engagement by the form mandrel and positioned to stop the axial movement of the form mandrel in said operating position with the proper spacing relative to the rollers, a feed plate adapted to axially engage the end of the cylinder workpiece and moving axially to force the cylinder end between the rollers and form mandrel after positioning the mandrel in said operating position, and means for simultaneously rotating the rollers and support spider whereby the bronze facing of the supporting members will slidily engage the cylinder preventing bulging while the rollers are forming the cylinder end against the form mandrel.

2. A mechanism for closing the end of a tubular cylinder which comprises a plurality of radially disposed circumferentially spaced rollers located in open relationship facing axially for receiving the axially moved end of a tubular cylindrical workpiece and having inwardly axially open endwise facing arcuate forming surfaces, a form mandrel having an annular arcuate convex forming surface facing the rollers and having a diameter to fit the interior of a hollow cylindrical tubular workpiece, means for positioning the form mandrel in a forming position to provide a work forming space between the mandrel and rollers, means for gradually relatively moving the tubular workpiece endwise over the mandrel with said mandrel in forming position into axial end forming engagement with the rollers with the inner surface of the workpiece supported by the forming surface of the mandrel, and means for relatively rotating the rollers about the mandrel forming surface whereby the end of the workpiece will be gradually and progressively formed in said work forming space.

3. A mechanism for closing the end of a tubular cylinder which comprises a plurality of circumferentially spaced rollers having a hollow curved groove in the surface and radially disposed to be located in an open axially facing position for receiving a cylindrical tubular workpiece in an endwise fashion, support members having curved inwardly facing surfaces located between the spaced rollers to lend support to the material formed by the rollers, a form mandrel having an annularly outwardly curved surface facing to cooperate with the rollers, means for moving the form mandrel in an axial direction

toward the rollers prior to advancing a tubular workpiece against the rollers, a stop member for the form mandrel positioned to terminate its axial movement at a forming position to provide a work forming space between the mandrel and rollers to receive the wall material of the cylindrical workpiece therebetween with the inner surface of the workpiece supported by the curved surface of the mandrel, means for advancing a workpiece axially over the mandrel into said work forming space, and means for rotating the rollers and support members relatively around the mandrel curved surface to form the end of the workpiece while the mandrel is in said forming position to thereby form the end of the workpiece.

4. A mechanism for closing the end of a hollow tube which comprises a form mandrel for insertion into the tube having an axially facing arcuate rounded surface against which the end of the tube is formed, a plurality of curved grooved forming rollers facing the rounded surface of the form mandrel with a forming space therebetween, supporting shoes positioned between the rollers to prevent bulging of the material as it is being formed, the forming space between the rollers and form mandrel being increasingly greater in the radially inward direction to accommodate increased thickness of the tube material as it is formed inwardly, means for forcibly advancing a tube axially over the mandrel into said forming space with the inner surface of the workpiece supported by the rounded surface of the mandrel, and means for relatively rotating the rollers and support shoes with respect to the tube material and form mandrel.
